UNITED STATES PATENT OFFICE.

EDGAR W. BELL, OF WILSON, OKLAHOMA.

LUG HOLDER.

Application filed August 22, 1923. Serial No. 658,787.

To all whom it may concern:

Be it known that EDGAR W. BELL, a citizen of the United States, residing at Wilson, in the county of Carter and State of Oklahoma, has invented certain new and useful Improvements in Lug Holders, of which the following is a specification.

This invention relates to a lug holder and has for its principal object to provide a simple and efficient means for use in connection with holding a lug of an underreamer while the same is being dressed and having been removed from the fire.

Another important object of the invention is to provide a lug holder of the above mentioned character, which is of such a construction as to enable various forms of lugs used in underreamers to be held by the holder and in a manner which will not injure or otherwise deface the lug while the same is being worked upon, previous to using the same in an underreamer.

A still further object of the invention is to provide a lug holder which is provided with means for positively holding the lug in a rigid position while the lug is undergoing the necessary treatment such as dressing the same and is also provided with means for enabling the person using the lug holder to hold the same in a convenient manner.

A further object of the invention is to provide a lug holder of the above mentioned character, which is simple in construction, inexpensive, strong, durable and further well adapted for the purpose for which it is designated.

Other objects and advantages of this invention will become apparent during the course of the following description:

In the accompanying drawings forming a part of this specification and in which like numerals designate like parts throughout the same:

Figure 1 is a side elevation of my lug holder.

Figure 2 is a top plan view thereof.

Figure 3 is a longitudinal section taken on line 3—3 of Fig. 2, and

Figure 4 is a transverse section taken on line 4—4 of Fig. 1, looking in the direction of the arrows.

In the drawings wherein for the purpose of illustration is shown the preferred embodiment of my invention, the numerals 1

and 2 designate generally a pair of pivoted cross levers. The lever 1 comprises an elongated member which has its forward end enlarged as shown at 3 and which gradually tapers rearwardly to form a reduced portion or handle 4. The enlarged portion 3 is furthermore provided with the vertically extending cutout portion 5 adjacent the forward end of the lever and the purpose of this construction will be hereinafter more fully described.

The forward end 3 is furthermore provided with the channel 6 which forms a substantially U-shaped jaw or section as more clearly shown in Fig. 4 of the drawings. The sides of the channel member 6 have their base portions provided with inwardly extending flanges 7 the purpose of which will hereinafter be more fully described.

The lever 2 is somewhat smaller than the lever 1 and the handle portion 8 thereof is adapted to extend over the top face of the handle portion 4 of the lever 1 in the manner as more clearly shown in the drawings. The forward end of the lever is provided with a downwardly extending portion 9 which is adapted to be received in the vertical cutout portion 5 provided in the enlarged forward end 3 of the lever 1 and the lower end of the downwardly extending portion 9 extends beyond the face of the lever 1 and terminates into a substantially flat jaw 10.

For the purpose of pivotally supporting the downwardly extending portion 9 of the lever 2, I provide a transversely extending pin or bolt 11 which acts as a pivot for pivotally supporting lever 2 on the lever 1. The pin 11 is furthermore adapted to support a suitable auxiliary handle 12 in a manner as more clearly shown in the drawings. The free end of the handle 8 of the lever 2 is furthermore provided with a cutout portion in the form of a wedge-shaped slot 13 and this slot 13 is adapted to receive the free end of the locking chain 14 which is secured at 15 to the top face of the handle on the lever 1 for the purpose of holding the lever 2 in a locked position with respect to the lever 1.

With a lug holder of the above mentioned character, its use in connection with holding the lug of underreamers when dressing the same after the lugs have been removed

from the fire will enable the person using the device to save considerable time in dressing the lug and furthermore will prevent the possibility of injury to the person while 5 working upon the lugs.

In use the lugs which are of the usual construction and are adapted to be taken from the underreamer and placed in a furnace or the like where it is heated for the purpose 10 of enabling the lug to be redressed in order to use the lug again in an underreamer; and by placing the lug in the channel 6 by any suitable means such as tongs so that the lug designated by the letter "A" will rest 15 upon the inwardly extending flanges 7 of the channel member 6 and by clamping the lever 2 together with the lever 1 the flattened jaw 10 will engage the bottom of the lug and hold the same firmly in a rigid 20 position in the channel 6 thereby enabling the lug to be worked upon in an easy and convenient manner. For the purpose of enabling the person to readily dress the lug while the same is held between the jaws 6 25 and 10 the auxiliary handle 12 may be grasped by the operator so as to enable the device to be properly supported.

As the lugs adapted to be held in my lug holder are of the usual construction found in 30 connection with underreamers, it is not thought necessary to go in detail as to the construction of the lug, it being sufficient to state that all of the lugs which are used in conjunction with the underreamers are provided 35 with the rounded outer surface so as to enable the same to fit properly in the channel portion of the U-shaped jaw 6. The flanges 7 furthermore act as guides for the lug when the same is inserted in the channel 40 portion of the U-shaped jaw 6 and there is no possibility of the lug becoming disfigured or otherwise defaced when held in the lug holder as would result if the lug were held between a pair of blacksmith tongs 45 as now used for this particular purpose.

The simplicity in which my lug holder is used enables the same to be readily and quickly handled and will do more sufficient work than any device which is now in use

for holding the lug while the same is being 50 treated.

From the foregoing description of the construction of my improved apparatus, it will be seen that I have provided a simple, inexpensive and efficient means for carrying 55 out the objects of the invention, and while I have particularly described the elements best adapted to perform the functions set forth, it is obvious that various changes in form, proportion and in the minor details of 60 construction may be resorted to, without departing from the spirit or sacrificing any of the principles of the invention.

What I claim as new and desire to secure by Letters Patent is:—

1. A lug holder of the class described comprising a pair of pivoted crossed levers, the jaw formed at the forward end of one of said levers being channeled to provide a substantially U-shaped jaw in transverse 70 section, the jaw of the other lever being substantially flat, and means for holding said levers and jaws in a locked position.

2. A lug holder of the class described comprising a pair of pivoted crossed levers, 75 the jaw formed at the forward end of one of said levers being channeled and substantially U-shaped in cross section, the sides of said channeled jaws provided with the inwardly extending flanges at their lower 80 ends, and the jaws of the other lever being substantially flat.

3. A lug holder of the class described comprising a lever provided with a vertical 85 cutout portion adjacent the enlarged forward end thereof, said enlarged forward end being further provided with a channeled jaw U-shaped in transverse section, the second lever having its forward end provided 90 with a downwardly extending portion extending through said vertical slot and pivotally supported therein, and a substantially flat jaw formed on the lower end of said downwardly extending portion and adapted to cooperate with said channeled jaw. 95

In testimony whereof I affix my signature.

EDGAR W. BELL
